UNITED STATES PATENT OFFICE.

JAMES P. EMERY, OF CHICAGO, ILLINOIS.

REFRIGERATOR.

SPECIFICATION forming part of Letters Patent No. 356,226, dated January 18, 1887.

Application filed January 26, 1886. Serial No. 189,855. (No model.)

To all whom it may concern:

Be it known that I, JAMES P. EMERY, a citizen of the United States, residing at Chicago, in the county of Cook and State of Illinois, 5 have invented certain new and useful Improvements in Refrigerators, of which the following is a specification.

My invention relates to refrigerators wherein an ice-chamber is arranged above a storage-chamber, and valved openings which provide means of communication between said upper and lower chambers are controlled automatically by opening and closing the doors of the storage-chamber to retain the cold air in and 15 prevent the admission of warm external air to the ice-chamber when the doors of the storage-chamber are open, and to effect a better circulation of air between the chambers when the doors of the storage-chamber are closed.

20 The object of my invention is to provide the greatest possible area of open and direct communication between the upper and lower chambers when the exterior doors of the storage-chamber are closed; to admit of a free circulation of air between the upper and lower chambers; to provide automatic means for closing communication between said chambers by the act of opening the door of the storage-chamber, and which will close such communication in closing the door; to provide means for regulating the area of opening between the chambers; to provide ample area and a direct and free downward course for the currents of cold air in their passage from the upper to the lower chamber; to provide protected passages of ample area and suitable direction for the escape of the expanded and saturated air from the lower to the upper chamber; to provide novel means for draining the floor of the ice-chamber, for catching the drip and conducting it away from the refrigerator; to provide a novel construction of double floor, the upper section of which supports the ice and the lower section of which 35 is provided with hinged pans which constitute in themselves shutters or valves to open and close communication between the upper and lower chambers, deflectors for conducting the ascending and descending currents of air, 40 and pans or receptacles for catching the water from the melting ice and preventing it from

falling through into the chamber below; and to provide certain details of construction, hereinafter more fully described.

In the accompanying drawings, Figure 1 is 55 a vertical sectional elevation of my improved refrigerator in the line *w w* of Fig. 2, looking toward the front; Fig. 2, a sectional plan in the line *x x* of Fig. 1; Fig. 3, a similar representation in the line *y y* in Fig. 1; Fig. 4, a 60 vertical sectional elevation in the line *z z* of Fig. 1, with the upper part of the ice-chamber broken away; Fig. 5, a plan of the upper section of the floor, seen from below, showing the chamber for the escape of the warmed and 65 vaporized air from the lower chamber to the side walls and thence to the ice-chamber; Fig. 6, a plan of one of the shutters, seen from below, which compose a section of the lower portion of the flooring, showing novel means 70 for securing and releasing their pivotal bolts.

The walls *A* of the refrigerator are built to form a rectangular or other suitably formed inclosure, with a suitable door, *B*, opening into the refrigerator-chamber *A'* and a door, *B'*, 75 opening into the ice-chamber *A''*. Bearing-posts *C* are built into the corners of the compartment and support a rectangular frame, *D*, which fits snugly around the interior of the chamber. The frame *D* is formed with cross-strips *d d'*, arranged alternately with and at equal distances from each other across the frame, to divide the floor into an even number of rectangular spaces. Each of the spaces is provided with a shutter or valve, *E*, pivotally 80 supported at its ends by sliding bolts *e*, which fit into bearing-sockets *e'* in the side of the frame, and are held securely in their sockets by a bar, *e''*, pivoted midway of its length to the under side of the shutter, to swing thereon and 85 abut against the inner ends of the bolts. When the bar *e''* is swung out of the way, the bolts can be withdrawn and the shutters removed 90 from the frame. (See dotted lines at Fig. 6).

The shutters *E* are supported midway of 95 their width to swing together in pairs across the openings in the frame *D*, and when closed rest with the lower edge of their remote sides upon the upper side of the depressed strips *d'*, and with the upper edge of their adjacent sides 100 resting upon the under side of the strips *d*. (See dotted lines at Fig. 1.) Three sets or

pairs of shutters are shown in the drawings, and it will be seen from the above-described arrangement that each set slopes slightly downward from their outer to their adjacent edges.

5 The shutters are operated simultaneously by a bar, F, hinged to hangers F', secured to the side of the frame D, and extending along one side of and beneath the entire length of the frame. Rods f connect the swinging sides of 10 the bar F with the remote sides of the shutters E, and serve to open and close the shutters by the swinging movement of the bar F. When the door B is opened, the bar F is pushed away from the frame D to close the shutters by a 15 spring-rod, G, secured midway of its length to the under side of the frame D, which presses with its free ends upon the upper side of the bar F and holds it down to close the shutters when the bar F is not acted upon by the door.

20 The free ends of the spring-rod G are held between plates g, and thus prevented from slipping off from the upper side of the bar when the latter is swung upon its hinges, as shown in Fig. 1. A hanger-plate, H, secured to and 25 depending from the bar E, carries a friction roller H', which is arranged about midway of the length of the bar and opposite to the upper corner of the swinging side of the door B. A cam-plate, I, is secured to the upper corner of 30 the swinging side of the door B, to project inwardly therefrom and push beneath the roller H' to swing the bar F and open the shutters as the door B is closed, and to hold the shutters open while said door is closed, and recede 35 from the roller to allow the shutters to close as the door B is opened, as hereinbefore described.

The plate I is made adjustable upon the door B by means of a slot, i, in the plate, and 40 a set-screw, i', which passes through the slot and clamps it at any required elevation upon the door, by which means the bar F may be lifted to a greater or less height, and the shutters may be opened to any required degree to 45 thus regulate the area of opening provided for the passage of air-currents from one chamber to the other.

The shutters E are formed with depressed upper surfaces, into which are fitted sheet-metal pans e³, to catch the drip from the melting ice, supported in a suitable manner above the pans. The pans e³ are each provided with discharge-spouts e⁴ at their adjacent lowest corners, and are arranged above a trough, K, 55 suspended upon brackets K', secured to the wall of the storage-chamber A, the said troughs serving to conduct the drip-water away from the refrigerator by means of suitable drain-pipes. (Not shown.)

50 A slatted frame, L, of well-known construction is arranged above the frame E to support the ice and admit of a free circulation of air around and beneath it. The slatted frame L rests upon the upper side of the frame M, and 55 is provided with cross-strips l at its ends, against which rest the lower ends of the slatted end frames, L', the upper ends of which rest

upon the side walls of the ice-chamber. Slatted side frames, L², rest upon the slatted floor L at their lower ends, and are supported at 70 their upper ends by the side walls of the ice-box, and thus provide a slatted crib for holding the ice from contact with the surfaces of the floor and wall in a well-known manner.

The frame L may rest directly upon the 75 frame E; but to provide a better circulation for the oppositely-moving currents of air, and to properly deflect and conduct the drip-water from the slatted frame L to the drip-pans e³, a frame, M, of novel construction is interposed between the frame E and the frame L, to rest upon the frame E and closely fit the inner sides of the walls of the refrigerator. The frame M is formed of side rails, m, which fit 80 closely against the side walls, A, of the refrigerator, and transverse bars m', which are arranged at equal distances from each other across the frame to provide a series of rectangular openings, m², arranged oppositely to the shutters E of the lower frame. 85

A supplemental frame composed of side rails, m³, supported upon and near the ends of the transverse bars m' parallel to the side rails, m, of the main frame, and cross-bars m⁴, secured to the ends of the side rails, m³, and arranged 95 immediately above the end transverse bars, m', of the main frame, provides an upper rim to the main frame, and also provides air-passages m⁵ upon the sides, and air-passages m⁶ upon the ends of the frame, through which the 100 warm-air currents may pass from below to the inner walls of the ice-chamber A², and follow said walls to the ice-chamber, to be cooled and condensed. The end cross-bars, m⁴ m⁴, of the supplemental frame are secured to the side 105 rails at a short distance from the ends thereof, to provide the air-passages m⁶, above described, and the lower outer edges of the end cross-bars, m⁴, are beveled to admit of the free movement of the air to the passages m⁶, which air is 110 deflected and directed thereto by the two shutters at the end of the refrigerator. The under side of the outer edges of the side rails, m³, and the upper edges of the inner sides of the side rails, m, are similarly beveled to admit of 115 the free movement of the air to the air-passage m⁵ from the channels m⁸.

The sides of the rectangular openings m² are bordered by beveled strips of molding m⁷, secured to the transverse bars m' and to the 120 side rails, m³, which thus form open panels with inwardly-sloping sides, to deflect the drip-water to the pans e³, secured to the upper sides of the shutters E.

The frame bars and moldings are covered 125 by a sheet-metal cap, M², made to snugly fit and conform to the upper and inner surfaces of the frame, and provide a smooth watertight non-corrosive surface for the water to drip upon from the superposed ice and conduct it to the pans suspended beneath the frame M.

The molding-strips m⁷ slope inwardly from the transverse bars m' and provide air pas-

sages or channels m^8 along the under sides of said bars and moldings and beneath the sheet-metal cap M², for the passage of upwardly-ascending air-currents to the air-passages m^5 m^5 5 and side walls of the ice-chamber.

The frames D and M may both be easily removed when desired for any purpose, and replaced without deranging the parts in any way.

10 The circulation and action of the air-currents within the refrigerator are as follows: The doors B' B of the ice-chamber and storage or refrigerating chamber, respectively, being closed, the shutters E will be tilted at angles in opposite directions by the door B, and the condensed dry air of low temperature will force its way downwardly from the upper or ice chamber and be concentrated and directed by the upper inclined sides of the shutters to the 15 lower or storage chamber in the direction of the arrows shown by full lines; and the vaporized air from below of a higher temperature, and consequently lighter specific gravity, will force its way upwardly in the direction of the site 20 directions by the dotted arrows beneath the inclined under sides of the shutters, by which it will be deflected and directed upwardly to the channels m^8 , formed in the under side of the frame M, which conduct the said air-currents laterally 25 to the air-passages m^5 , formed at the sides of the frame M, from whence these air-currents escape to the ice-chamber, where the air is again condensed and cooled by contact with the ice and caused to again descend to the 30 chamber below. The ascending air, which strikes the two shutters at the ends of the refrigerating-chamber, will be deflected by said shutters and directed by the air-passages m^6 to the ice-chamber. When the door B of the refrigerating-chamber is open, the shutters will completely close communication between the upper and lower chambers, and the warm exterior air which fills the lower or storage chamber is thus prevented from rushing up into 35 the ice-chamber, and the refrigerated air of the ice-chamber is closely pent up and prevented from escaping to the chamber below so long as the door B of said chamber is open. In closing the door of the storage chamber the 40 shutters will swing open across the entire area beneath the floor and form inclined deflectors, which will direct and concentrate both the upwardly and downwardly moving currents to facilitate their displacement one for the other 45 and permit the pent-up volume of cold air, which, because of its confinement in the ice-chamber, has fallen to a much lower temperature than that of the refrigerating-chamber, to escape with its full force and accumulated 50 density and dryness, to suddenly and completely displace the air of the storage-chamber before the dryness of the descending currents can be materially affected by commingling with the upwardly-moving saturated currents, 55 by which means the air in the storage-chamber is kept dry and pure, as the impure gases and

bad odors are carried upwardly with the vaporized air, and upon condensation are carried off with the water deposited in the upper chamber through the channels above described. 70

I claim as my invention and desire to secure by Letters Patent—

1. In a refrigerator, the combination, with the upper and lower chambers, of a division-floor arranged between the chambers formed of an apertured frame-work, and a series of hinged shutters arranged in pairs beneath the apertures, and adapted to open and close together in opposite directions, substantially as 75 80 and for the purpose described.

2. The combination, with a refrigerator, of a frame-work adapted to fit the inner walls of the inclosure to be applied to and removed therefrom, and provided with shutters hinged 85 thereto, to operate substantially as and for the purpose specified.

3. In a refrigerator, the combination, with the upper and lower chambers, of hinged shutters arranged to open and close communication 90 between said chambers, an arm operated upon by the movement of the door, and an adjustable plate secured to the door to operate the shutters and regulate the extent of their movement, substantially as described. 95

4. In a refrigerator, the combination, with the upper and lower chambers, of a division-floor formed of an open frame-work, the under side of which is channeled to provide conduits for the escape of vaporized and heated currents 100 of air to the side-wall passages, and valved openings between said channeled frame-work, substantially as and for the purpose described.

5. In a refrigerator, the combination, with the upper and lower chambers, of a division-floor formed of an open frame-work provided with channels for the escape laterally of the upwardly-moving currents of air, and hinged shutters arranged in pairs beneath the openings in the frame-work to deflect both the upwardly and downwardly moving currents, substantially as described. 105 110

6. In a refrigerator, the combination, with the upper and lower chambers, of a division-floor formed of an open frame-work provided with channels for the escape laterally of vaporized and heated currents and passages between the side walls and open frame-work communicating with said lateral passages, substantially as and for the purpose described. 115 120

7. The combination, with the perforated floor of a refrigerator, of pans hinged thereto to catch the drip, and also serve as deflectors for currents of air passing through openings in the floor, substantially as described. 125

8. The combination, with the perforated floor of a refrigerator, of pans hinged thereto to provide valves which close upon themselves to cut off the flow of air through the openings in the floor, which serve to deflect said air-currents, and which provide drip-pans beneath the perforated floor, substantially as described. 130

9. The shutters, in combination with sliding bolts supported at their ends to provide pivotal connection with the exterior frame, and the longitudinal bar e^3 , pivotally connected to 5 the under side of the shutter to abut against the inner ends of the sliding bolts, substantially as and for the purpose described.

In testimony whereof I affix my signature in presence of two witnesses.

JAMES P. EMERY.
